UNITED STATES PATENT OFFICE

HEINRICH BECKER, OF AUGSBURG, GERMANY, ASSIGNOR TO THE FIRM MASCHINEN-FABRIK AUGSBURG-NUERNBERG, AKTIENGESELLSCHAFT, OF AUGSBURG, GERMANY, A CORPORATION OF GERMANY

DOUBLE-ACTING TWO-STROKE COMBUSTION ENGINE WITH SLOT SCAVENGING

Application filed June 14, 1928, Serial No. 285,435, and in Germany June 24, 1927.

This invention relates to engines of the two-cycle type and more particularly to two-cycle engines having so-called reverse scavenging.

placed axially of the cylinder, the inlet openings or slots *a* being adapted to be uncovered by the piston end after the latter has uncovered the outlet or exhaust slots *b*. The engine is of the so-called reverse scavenging type in which the scavenging air entering the cylinder through the inlet openings *a* is deflected from the upper surface of the piston along the opposite cylinder wall to the cover or head of the cylinder, then back down along the cylinder wall above the inlet openings and then toward the outlet slots. In accordance with this invention however, the reverse scavenging is such that the scavenging flow attains a speed component in a circumferential direction substantially around the cylinder axis. This whirling motion of the combustion air provides for an intimate mixture of the fuel which is injected by the usual fuel nozzle or nozzles, as shown, provided preferably in the combustion head portion of the cylinder.

- 5 One object of the invention is the provision of an engine of this character having inlet and outlet openings or slots in the cylinder walls so arranged with relation to each other as to cause the resultant direction of 55
10 the total stream entering the cylinder through the inlet openings to be displaced angularly in a circumferential direction from the resultant direction of the total stream leaving the cylinder through the outlet openings. 60
15 Another object of the invention is the provision of a double-acting oil engine of the character mentioned in which the inlet openings or slots are arranged unsymmetrically and in axially separated planes with respect 65
20 to the group of outlet openings or slots.

Further objects and advantages of the invention will be apparent from the following description and from the accompanying drawing, in which—

- 25 Fig. 1 is a view in longitudinal section of one form of the invention;
Fig. 2 is a diagrammatic showing in section of the form of the invention illustrated in Fig. 1;
30 Fig. 3 is a perspective view of the cylinder of a modified form of construction;
Fig. 4 is a view in section corresponding to Fig. 3;

- 35 Fig. 5 is a further form of construction illustrated in perspective; and
Fig. 6 is a sectional diagrammatic view of the invention as applied to the stuffing box side of a double-acting engine.

In the construction illustrated in Figs. 1 40 and 2 the engine is of the oil-injection two-cycle type, Fig. 1 representing one cylinder end of a double-acting engine. The engine may operate on the self-ignition principle or in other words is of the Diesel type. The 45 cylinder walls are provided with slotted inlet and outlet openings adapted to be opened and closed by the piston which operates longitudinally of the cylinder. The inlet and 50 outlet openings are preferably arranged as shown in this figure in different planes dis-

75 The whirl of the combustion air entering through the inlet openings is attained in accordance with this invention by so arranging the inlet and outlet slots or openings through which the scavenging and combustion air flows that the resultants of the direction of the total stream entering the cylinder is displaced angularly in a circumferential 80 direction from the resultant direction of the total stream leaving the cylinder. The inlet openings are preferably arranged as a group of spaced-apart slots, these inlet slots being provided unsymmetrically with relation to the cylinder walls and not extending clear around the cylinder. The outlet slots are also arranged in a group unsymmetrically positioned on the cylinder walls and spaced from the inlet slots in the direction of the 85 length of the cylinder.

90 As shown in Figs. 1 and 2 the inlet slots extend throughout a segment of the cylinder as indicated between the points A and B. The line C D divides the segment A B in half. The point E displaced angularly from the point C a considerable distance is substantially the common meeting point of the various individual streams entering the cylinder through the inlet openings *a*, it being 95 100

understood that the various inlet openings are so directed or focused as to create a resultant flow of the total inlet stream in the direction of the line F E, displaced considerably from the medial line C D of the various inlet slots. It is apparent therefore that in this form of construction the resultant direction of the total stream entering the cylinder is in such direction as to tend to create a whirl 5 in a counter-clockwise direction as viewed from above. The outlet slots *b* are preferably arranged in this form of construction substantially coextensive in a circumferential direction with the extent of the inlet slots the 10 outlet slots being so arranged as to cause the total stream of the gases leaving the cylinder to be directed through the exhaust slots in a direction which is considerably displaced from the direction of the total stream entering the cylinder. The dotted line in Fig. 1 indicates the reverse scavenging flow direction as combined with the whirling direction imparted to the flow in the manner just mentioned. In this manner an intimate mixture 15 of the fuel with the combustion air entering through the inlet openings or slots *a* is attained and the efficiency and power of the engine is increased. It is apparent that due to the whirling action about the cylinder axis 20 while the gases are flowing through the cylinder with the inlet and outlet slots open, the whirl will continue due to the inertia of the gases during the compression stroke so that when the fuel injection finally takes place 25 the gases will still be moving about the engine axis and will flow past the injection nozzle for the efficient utilization of the gas and fuel. Due to the intimate mixing of the fuel and air higher speeds of operation of this type of 30 engine may be attained in an efficient manner, and the engine is especially suitable for solid injection working.

In the construction illustrated in Figs. 3 and 4 the inlet openings *a* are arranged in a group which is displaced angularly in a circumferential direction from the group of outlet openings *b*. Thus the inlet openings *a* are provided in the cylinder wall between the points A and B and the outlet openings *b* 45 are provided in the segment of the cylinder walls between the points A' and B'. The two groups of openings are therefore unsymmetrically arranged with relation to each other. The inlet openings cause the scavenging and 50 combustion air entering the cylinder to have a resultant direction along the line C D over the piston head. The flow of the exhausting gases is in the direction D' C', being the dividing line between the points A' and B'. Thus 55 it is apparent that the direction of the total stream entering the cylinder is displaced a considerable angle in the circumferential direction from the total stream leaving the cylinder. The stream entering the cylinder after 60 passing over the cylinder head in the general

direction C D travels up along the opposite side of the cylinder, is then deflected downwardly by the cylinder cover or head, and after traveling down the side of the cylinder substantially above the inlet opening it is 65 directed out of the exhaust slots *b* in such a direction as to create a whirl in a counter-clockwise direction as viewed in Fig. 4, and the flow therefore assumes a loop formation as 70 shown in Fig. 3 to cause a continued whirl about the cylinder axis after the slots *a* and *b* are closed by the piston, conducive to an intimate mixture of the injected fuel and the 75 combustion air.

In Fig. 5 is shown a further form of construction which is similar to that shown in Figs. 3 and 4 in that the inlet and outlet openings *a* and *b* are arranged in planes displaced axially of the cylinder and arranged unsymmetrically with relation to each other 80 so that above some of the inlet openings *a*, as indicated at *c*, no outlet openings are provided, and below some of the outlet openings *b*, as indicated at *d*, there are no inlet openings. The scavenging streams will therefore 85 enter the cylinder in a direction angularly displaced in a circumferential direction from the resultant stream of gases leaving the cylinder and therefore the gases in the cylinder will whirl about the cylinder axis. However, 90 in the form of construction shown in Fig. 5 the inlet slots *c* are elongated in the direction of the cylinder axis towards the zone of the exhaust slots and the exhaust slots *d* are elongated in the direction of the cylinder axis 95 towards the zone of the inlet scavenging slots. According to this construction the effect of 100 continuing or elongating the inlet slots *c* above which no outlet slots are provided, and the effect of continuing or elongating the slots *d* under which no inlet slots are provided is to increase the angular displacement 105 of the resultant directions of the total inlet and outlet streams. This is true due to the 110 fact that the extension of the slots *c* and of the slots *d* permits an increased flow through these slots, which are arranged in the greatest angular displacement with respect to each other.

Fig. 6 shows an arrangement of the scavenging and exhaust slots on the stuffing box side of a double-acting machine of this character. In this form of construction, as indicated in section in this figure, the inlet slots are arranged on one side of the cylinder to 115 create streams of scavenging air directed to each side of the piston rod, and the exhaust slots are also arranged, preferably unsymmetrically with relation to the inlet slots so 120 that the resultant direction of the outflowing gases is at a considerable angle to the resultant direction of the gases flowing into the cylinder, by permitting the division of the gases around the piston rod in such a manner as to create a whirling action around the 125 130

5 piston rod which may continue after the inlet and outlet slots are closed by the piston. The arrows shown in this figure indicate the inflowing and outflowing streams of gases and show how the streams whirl about the piston rod.

10 While the forms of apparatus herein described constitute preferred embodiments of the invention, it is to be understood that the invention is not limited to these precise forms of apparatus, and that changes may be made therein without departing from the scope of the invention which is defined in the appended claims.

15 What is claimed is:

1. An internal combustion engine of the two-cycle type having a cylinder provided with scavenging outlet and inlet openings provided in adjacent portions of the cylinder wall for reverse scavenging flow, a piston operating in said cylinder, the outlet and inlet openings as groups being unsymmetrically arranged in a circumferential direction with relation to each other to cause the resultant direction of the total stream entering the cylinder through the inlet opening to be displaced angularly in a circumferential direction from the resultant direction of the total stream leaving the cylinder through the outlet opening.

2. An internal combustion engine of the Diesel type having a cylinder provided with scavenging outlet and inlet openings provided in adjacent portions of the cylinder wall for reverse scavenging flow, a piston operating in said cylinder and adapted to open and close said openings, the outlet and inlet openings as groups being arranged unsymmetrically in a circumferential direction with relation to each other in different but overlapping circumferential bands to cause the resultant direction of the total stream entering the cylinder through the inlet openings to be displaced angularly in a circumferential direction from the resultant direction to the total stream leaving the cylinder through the outlet opening.

3. An internal combustion engine of the Diesel type having a cylinder provided with outlet and inlet openings and a piston operating in said cylinder, the outlet and inlet openings as groups being arranged unsymmetrically in a circumferential direction with relation to each other to cause the resultant direction of the total stream entering the cylinder through the inlet openings to be displaced angularly in a circumferential direction from the resultant direction of the total stream leaving the cylinder through the outlet openings for the creation of a whirling action of the gases about the cylinder axis.

4. An internal combustion engine of the two-cycle type having a cylinder provided with scavenging outlet and inlet openings provided in adjacent portions of the cylinder

wall for reverse scavenging, a piston operating in said cylinder and cooperating with said outlet and inlet openings to open and close the same, there being a group of spaced inlet openings provided in an unsymmetrical manner in the cylinder walls and a group of outlet openings provided in an unsymmetrical manner in the cylinder walls the two groups being arranged unsymmetrically in circumferential directions with respect to each other and in axially separated planes to cause the resultant direction of the total stream entering the cylinder through the inlet openings to be displaced angularly in a circumferential direction from the resultant direction of the total stream leaving the cylinder through the outlet openings.

5. A double-acting engine of the two-cycle type operating with fuel injection having a cylinder provided with scavenging outlet and inlet openings provided in adjacent portions of the cylinder wall for reverse scavenging, a piston operating in said cylinder and cooperating with said outlet and inlet openings to open and close the same, there being a group of spaced inlet openings provided in an unsymmetrical manner in the cylinder walls and a group of outlet openings provided in an unsymmetrical manner in the cylinder walls the two groups being arranged unsymmetrically in circumferential directions with respect to each other and in axially separated planes to cause the resultant direction of the total stream entering the cylinder through the inlet openings to be displaced angularly in a circumferential direction from the resultant direction of the total stream leaving the cylinder through the outlet openings for the creation of a whirling action of the gases about the cylinder axis, the group of inlet openings containing some which are elongated in the direction of the cylinder length, and the group of outlet openings containing some which are elongated in the direction of the cylinder length, the elongated inlet openings being elongated toward the plane of the outlet openings and the elongated outlet openings extending toward the plane of the inlet openings.
